(57) **CLAIM**

The ornamental design for a carrying bag, as shown and described.

DESCRIPTION

FIG. 1 is a front, left and top perspective view of a carrying bag showing our new design;

FIG. 2 is a rear, right and top perspective view thereof;

FIG. 3 is a front elevational view thereof;

FIG. 4 is a rear view thereof;

FIG. 5 is a right view thereof;

FIG. 6 is a left elevational view thereof;

FIG. 7 is a top plan view thereof;

FIG. 8 is a bottom plan view thereof;

FIG. 9 is an enlarged view of a portion labeled as 9 on FIG. 1;

FIG. 10 is an enlarged view of a portion labeled as 10 on FIG. 1; and,

FIG. 11 is an enlarged view of a portion labeled as 11 on FIG. 2.

The long dash-short dash broken lines depict enlargement boundaries that form no part of the claimed design.
